(57) **CLAIM**

The ornamental design of a UV lamp for nail drying, substantially as shown and described.

DESCRIPTION

FIG. 1 is a front perspective view of a UV lamp for nail drying in accordance with the present invention.

FIG. 2 is another perspective view of a UV lamp for nail drying in accordance with the present invention.

FIG. 3 is another perspective view of a UV lamp for nail drying in accordance with the present invention

FIG. 4 is a rear view thereof.

FIG. 5 is a left end view thereof.

FIG. 6 is a right end view thereof.

FIG. 7 is a top view thereof; and,

FIG. 8 is a bottom view thereof.

The broken lines shown in the drawings represent unclaimed subject matter and form no part of the claimed design.
